UNITED STATES PATENT OFFICE.

EDWARD E. WHITMORE, OF CHICAGO, ILLINOIS, ASSIGNOR TO THE CURTAIN SUPPLY COMPANY, OF CHICAGO, ILLINOIS, A CORPORATION OF ILLINOIS.

METAL SHADE ROLLER.

Application filed December 24, 1919. Serial No. 347,144.

To all whom it may concern:

Be it known that I, EDWARD E. WHITMORE, a citizen of the United States, residing at Chicago, in the county of Cook and State of Illinois, have invented certain new and useful Improvements in Metal Shade Rollers, of which the following is a specification.

The roller of my invention, while applicable to general use, is particularly designed for any situations demanding a fixture on graceful light lines and of slighty appearance, as in motor cars and the like.

The principal characteristics of the invention are the formation of brackets from sheet metal stampings in association with the metal barrel, the manner of assemblage with the brackets of the bearing studs for the roller, the securing of the end caps to the barrel, the anchoring of the barrel spring to the cap, the centering of the caps on the barrel, the protection of the pawls against displacement, and various other constructional advantages cooperating to produce a shade roller of efficiency and pleasing appearance at low cost, not liable to get out of repair or adjustment, and having no brazed or soldered joints inviting rust.

Heretofore it has been usual in all-metal shade fixtures to solder or braze the permanently connected parts. This introduces an element of deterioration and ultimate disintegration due to the acid fumes attacking the adjacent parts, and especially the spring in the barrel. This is avoided in the present invention by the use of mechanical connections throughout as distinguished from soldered or brazed joints.

In order that the invention may be readily understood and the characteristic features thereof appreciated a preferred embodiment of the same is set forth in the accompanying drawing and in the following detailed description based thereon. Obviously as the invention is susceptible of embodiment without strict adherence to the details of construction as exemplified, the drawing and description are to be taken as illustrative and not in an unduly limiting sense.

In the drawing—

Fig. 1 is a top plan view of my improved shade roller in operative connection to a window opening;

Fig. 2 is a side elevation of the same; Fig. 3 is an enlarged horizontal section taken on the line 3—3 of Fig. 2 with the central portion broken away;

Fig. 4 is a face view of the pawl-bearing end cap;

Fig. 5 is a side elevation of the roller end carrying the cap shown in Fig. 4;

Fig. 6 is a face view of the cap at the opposite end of the roller;

Figs. 7 and 8 are respectively face and edge views of the bracket adapted to receive that end of the roller provided with the pawls; and

Figs. 9 and 10 are respectively edge and face views of the bracket at the opposite end of the roller.

Having reference to the drawing more in detail the shade roller is shown as comprising a barrel 11 of sheet metal tubular in form with open ends. As most clearly shown in Fig. 3, the barrel is provided at its two ends with projecting arcuate tongues 12 adapted to be received within arcuate slots 13 stamped in metal disks forming caps 14 and 15. The tongues 12 project through the slots 15 and are upset as shown in the drawing and consequent disassociation of the barrel and the caps is prevented.

The cap 14 has impressed therein arcuate depressions 16 forming on the inner face thereof arcuate ribs, the distance separating the ribs being slightly less than the interior diameter of the barrel 11 whereby the said ribs serve as positioning means for the cap with reference to the barrel.

At the opposite end of the roller the cap 15 is positioned with reference to the barrel not only by the tongues 12 seated within the slots 13 but also by the marginal portions 17 of a depressed portion 18 of the cap forming a boss on the inner face of the cap and a cavity on the outer face thereof.

The cap 15 likewise has struck up from the outer face thereof lugs 19 which serve as abutments to limit the outward swing of pawls 20 pivoted thereon at 21.

Within the barrel 11 is longitudinally disposed an axle 22 with one or both of its ends projecting therefrom through the central apertures 23 of the caps 14 and 15. About the axle 22 is disposed a coil spring 24 having one end secured to the axle at 25 and the other end to the barrel, being

here shown as anchored within an opening 26 of the ear formed by the inward depression of the metal at 17. Within the coiled spring 24 and about the axle 22 is arranged 5 a tubular piece of fabric 27 whereby any rattling by reason of contact between the spring and axle is prevented.

Upon the window casing 28 at spaced intervals corresponding to the length of the 10 capped roller 11 are mounted two members of a pair of brackets providing bearing seats for the ends of the axle 22. The brackets are counterparts in so far as the body portion of the same is concerned and they are 15 formed by stamping from thin sheet metal such as brass into an integral whole comprising a semi-spherical body portion 29, a pedestal 30 and horizontally disposed base or leg portion 31. The face of each of the 20 brackets is in a vertical plane and of a cross-sectional extent slightly less than that of the caps 14 and 15 designed to rotate closely adjacent thereto. The area embraced by the bracket face 29 is sufficiently large 25 to include the pawls 20, here shown as provided with pivots 21 and abutments 19, so as to effectually house the same and form a casing within which such parts revolve and function.

30 One of the brackets, shown at the right hand of the figures in the drawing, is provided with a bearing stud 32 of metal having its end 32^a reduced and seated within the central portion of the bracket body 29 and upset or riveted to prevent its dislodgement. The companion bracket at the left hand end is provided with a bearing stud 33 similarly mounted within the bracket but differing from the stud 32 in that it is of 35 a greater length and projects slightly beyond the face of the bracket and is also provided with a recess or slot 34 in its side wall adjacent to its end, the said recess cooperating with the pawls 20 to permit the rotation 40 of the roller in one direction and to check its rotation in the other, the action of the pawls being controlled by gravity and centrifugal force in the well known manner without the use of actuating springs. The 45 projecting end of the bearing stud 33 is accommodated within the cavity at 18 provided by the inward depression of the metal. This projecting of the stud end into the cavity brings the pivotal points of the pawls 20 into 50 a plane which includes the stud and effectually prevents any interference with the operation of the roller by the accidental dropping of the pawls over the end of the stud.

55 The spring 24 is not only placed under angular tension by the "winding" of the roller after being seated within the brackets but its length is such that it is at all times under longitudinal tension whereby to hold 60 the roller as an entirety resiliently pressed

against the left hand bracket, thus preventing any tendency of the mechanism to rattle in case the brackets should not be accurately adjusted as to position. It will be understood that the two ends of the axle 22 are 70 frictionally fixed within the bearing studs 32 and 33 against withdrawal and turning, they each being slightly deformed as indicated at 22^a and being forcibly seated within the bearing studs. 75

I claim:

1. In a metal shade roller, a barrel, caps at the end thereof, an axle extending longitudinally of the barrel with ends projecting through the caps, a spring surrounding the axle with one end attached thereto and the other end to one of the caps, stamped metal concave brackets facing the roller ends, bearing studs for the axle disposed within the brackets and having openings aligned with the axle, one of said studs having a lateral recess, and pawls mounted on the adjacent cap and adapted alternatively to engage the recess. 80

2. In a metal shade roller, a barrel, caps at the end thereof, an axle extending longitudinally of the barrel with ends projecting through the caps, a spring surrounding the axle with one end attached thereto and the other end to one of the caps, stamped metal concave brackets facing the roller ends, bearing studs for the axle disposed within the brackets and having openings aligned with the axle, one of said studs extending beyond the general plane of the cap into the barrel end and having a lateral recess, and pawls mounted on the cap and overhanging the recess for alternatively engaging therein. 95

3. In a metal shade roller, a barrel, caps at the end thereof, an axle extending longitudinally of the barrel with ends projecting through the caps, a spring surrounding the axle with one end attached thereto and the other end to one of the caps, stamped metal concave brackets facing the roller ends, bearing studs for the axle disposed within the brackets and having openings aligned with the axle, one of said caps having the metal of its central portion depressed into the barrel end to form an outwardly facing cavity, the adjacent one of said studs extending beyond the general plane of the cap into the cavity and also having a lateral recess, and pawls mounted on the cap and overlying the cavity for engaging alternatively within the recess. 110

4. In a metal shade roller, a barrel, caps at the end thereof, an axle extending longitudinally of the barrel with ends projecting through the caps, a spring surrounding the axle with one end attached thereto and the other end to one of the caps, stamped metal concave brackets facing the roller ends, bearing studs for the axle disposed within 115 120 125 130

the brackets and having openings aligned within the axle, said bearing studs having their ends reduced and upset within the pressed metal body of the bracket to prevent withdrawal, one of the studs having a lateral recess, and pawls mounted on the adjacent cap for alternatively engaging the recess.

5. A metal shade roller, a barrel, and end caps therefor, having arcuate slots, the barrel having arcuate projecting tongues extending through the slots and upset to secure the caps at the barrel ends, one of said caps having the metal of its central 10 portion depressed into the barrel end to form an inwardly projecting positioning portion and an outwardly facing cavity, pawls mounted on the face of said caps and overhanging the cavity, the depressed portion 15 of the metal in the cap providing an apertured ear, an axle disposed within the barrel with its ends projecting through the caps, a spring disposed about the axle with one end attached thereto and the other end 20 anchored in the ear, in combination with pressed metal brackets having semi-spherical body portions facing towards the caps of the roller, bearing studs for the axle ends disposed within the brackets with their ends 25 seated in the walls thereof and upset to prevent disassociation, one of said studs extending beyond the plane of the cap into the cavity formed therein and also having a lateral recess within the plane of the pawls 30 mounted on the cap.

35 6. In a metal shade roller, a barrel having arcuate projecting tongues at its ends, and end caps for the barrel having arcuate slots for the reception of the tongues, said tongues upset to secure the caps at the barrel ends, the caps having arcuate positioning ribs formed therein and projecting within the barrel ends, one of the caps having an ear punched inwardly therefrom and a pair 40 of lugs punched outwardly therefrom, an axle disposed within the barrel with its ends projecting through the caps, a spring disposed about the axle with one end attached thereto and the other end anchored 45

in the ear, and pawls pivoted on the outer 50 face of the cap provided with the lugs and abutting thereagainst to limit their movement.

5. In a metal shade roller, a tubular open ended barrel, and end caps therefor having 55 arcuate slots, the barrel having arcuate projecting tongues extending through the slots and upset to secure the caps at the barrel ends, the width of each tongue being equal to or greater than the radius of the barrel. 60

8. In a metal shade roller, a barrel, caps at the end thereof, an axle extending longitudinally of the barrel with ends projecting through the caps, a spring surrounding the axle with one end attached thereto and the 65 other end to one of the caps, stamped metal concave brackets facing the roller ends, bearing studs for the axle disposed within the brackets and having openings aligned with the axle, said bearing studs being upset 70 within the pressed metal body of the bracket to prevent withdrawal, one of the studs having a lateral recess, and pawls mounted on the adjacent cap for operatively engaging the recess. 75

9. In a shade roller, a hollow barrel, an axle therein, a spring also within the barrel having one end affixed relative thereto and the other end affixed relative to the axle, and bracket mountings for the roller, the 80 spring under longitudinally acting stress whereby to press a roller end against one of the brackets.

10. In the shade roller, a hollow barrel, an axle therein, a torsion spring within the 85 barrel about the axle and having one end affixed relative to the axle and the other end affixed relative to the barrel, and bracket mountings for the roller, the spring under longitudinally acting stress whereby to 90 press a roller end against one of the brackets.

In witness whereof I have hereunto signed my name in the presence of two subscribing witnesses.

EDWARD E. WHITMORE.
